[57] CLAIM

The ornamental design for an adjustable lamp, as shown and described.

DESCRIPTION

FIG. 1 is a perspective view of an adjustable lamp showing my new design;

FIG. 2 is a top plan view of the lamp head on an enlarged scale;

FIG. 3 is a bottom plan view of the lamp head on an enlarged scale;

FIG. 4 is a side elevational view of the lamp head on an enlarged scale, the opposite side of the head being a mirror image;

FIG. 5 is a perspective view of a second embodiment of my new design;

FIG. 6 is a side elevational view of the first embodiment, the opposite side being a mirror image;

FIG. 7 is a top plan view of the first embodiment;

FIG. 8 is a bottom plan view of the first embodiment;

FIG. 9 is a rear elevational view of the first embodiment; and,

FIG. 10 is a front elevational view of the first embodiment.

The articulated support is omitted in FIGS. 2, 3, and 4 for convenience of illustration.

The second embodiment differs from the first embodiment only by the reduced length of the articulated supports.

The base is shown in broken lines in FIGS. 1 and 5 for illustrative purposes only.
